CABINET SINK

Robert W. Hyde, Cincinnati, Ohio; assignor to American Radiator & Standard Sanitary Corporation, New York, N.Y., a corporation of Delaware

Application April 1, 1957, Serial No. 45,512

Term of patent 14 years

(Cl. D4—2)

FIG. 1

FIG. 2

FIG. 3

FIG. 4

Fig. 1 is a top plan view of a cabinet sink showing my new design.

Fig. 2 is a front elevational view thereof;

Fig. 3 is a left end elevational view thereof; and

Fig. 4 is a right end elevational view thereof.

The dominant features of my design reside in the portions shown in full lines.

I claim:

The ornamental design for a cabinet sink, substantially as shown and described.
